UNITED STATES PATENT OFFICE.

ADEN J. ASHLEY, OF CHICAGO, ILLINOIS, ASSIGNOR OF ONE-HALF TO JESSE L. HONTZ, OF SAME PLACE.

ADJUSTABLE SASH-LOCK.

SPECIFICATION forming part of Letters Patent No. 587,294, dated August 3, 1897.

Application filed September 2, 1896. Serial No. 604,643. (No model.)

To all whom it may concern:

Be it known that I, ADEN J. ASHLEY, a citizen of the United States, residing at Chicago, in the county of Cook and State of Illinois, have invented certain new and useful Improvements in Adjustable Sash-Locks, of which the following is a specification.

This invention relates to certain new and useful improvements in sash-fasteners; and 10 it has for its object to provide a simple, effective, and inexpensive fastener which shall be absolutely burglar-proof; and with these objects in view the invention consists in the novel construction, arrangement, and combination of the parts hereinafter more fully 15 described.

In the accompanying drawings, forming a part of this specification and in which like 20 letters and numerals of reference indicate corresponding parts, Figure 1 is a front elevation of a window-sash with the invention applied thereto, the lower sash being shown partially elevated. Fig. 2 is a longitudinal sectional view thereof with the window-sashes in their 25 closed positions. Fig. 3 is a detail perspective view of a locking device in its unlocked position, parts of the guide-rod being broken away. Fig. 4 is a sectional view of the same, and Fig. 5 is a similar view of a modification.

30 I am aware that heretofore sash-fasteners have been devised embodying the general characteristics of my invention—that is to say, such fasteners consist of a guide-rod carried upon one sash or upon the window-frame and coöperating with a locking device carried upon the other sash, whereby the sashes may be locked in their closed position or in a partially-opened position. These prior 35 constructions are all more or less objectionable, however, for many reasons, chiefly on account of their lack of simplicity and strength. Another objection to such fasteners arises from the fact that they project from the inside of the window-sashes to such an 40 extent as to interfere with the window-drapes and prevent the use of the ordinary roller-shade. It is the aim of the present invention not only to provide a simple and inexpensive sash-fastener, but to cure the 45 50 objectionable features of prior analogous devices.

Referring more particularly to the drawings, A designates the window-frame, and B C the upper and lower sashes, respectively. The sashes are suitably guided on the window-frame and may or may not be provided with the usual weights and cords. The opposing faces of the lower and upper bars 1 2 of the sashes B C, respectively, are oppositely beveled and form a tight joint when the 55 sashes are in their closed positions, and the face of the sash-bar 2 is provided with a recess 3, while to that of the sash-bar 1 is secured a plate 4, having a projecting threaded socket 5, which normally extends into the recess 3. 60

The upper bar of the sash B is provided with a plate 6, having a threaded projecting socket 7, similar to that upon the lower sash-bar and in vertical alinement therewith, said 70 plates and sockets being shown located intermediate the side bars of the sash or opposite same.

Supported wholly upon the upper sash B is a notched guide-rod D, having its ends 75 screw-threaded and fitted into the sockets 5 and 7, whereby said rod is rigidly supported, and when the sashes are raised or lowered extends through the recess 3 and lies between the glasses of the sashes and out of position 80 to be interfered with. It is to be noted, too, that the plate 4 never extends above or below the lower sash, and therefore it is impossible to get access to and remove it without first removing one of the sashes from the 85 window-frame or removing the glass of the lower sash. Consequently it would avail an intruder nothing to remove the top supporting-plate 6, as the rod D would still be firmly supported in the socket of the lower plate 4. 90

Supported upon the top of the upper sash-bar of the sash C in position to coöperate with the guide-bar D is a locking device E. This locking device may be variously constructed, but I prefer to employ the construction shown 95 on account of its effectiveness and simplicity. As shown, the locking device consists of a securing-plate 8, provided with a head 9, from one side of which extends a vertical recess 10 for reception of the guide-bar D. In the sides 100 of the head is formed a semiannular recess 12, which intersects the vertical recess 10 and re-

- ceives a segmented locking-piece 13, having a thumb-piece 14, a space 15 being left between the arms of the locking-piece sufficiently wide to permit the lateral insertion of the guide-rod in the recess 10 when said space is in alignment with the recess, and when in this position the guide-rod is unlocked and either sash may be raised or lowered, as desired. If, however, the locking-piece be shifted to the right or left of the above-described position its inner face enters one of the notches in the opposing face of the guide-rod and prevents the longitudinal movement of the rod in the vertical recess.
- 5 While in Figs. 1 to 4 I have shown the guide-rod as provided with notches, it will be understood that they may be omitted and the friction between the contacting surfaces of the locking-piece and guide-rod be alone depended upon to lock them together, as shown in Fig. 5. It will be obvious, also, that the locking-piece may be in the form of a ring instead of a segment and that other similar modifications may be made without departing 5 from the spirit of the invention.

From the above description it will be seen that when the window-sashes are in their closed locked positions, as shown in Fig. 2, no movement whatever is permitted them. When, however, a sash is partially raised or lowered and then locked in such position, the sashes may be moved simultaneously up or down, accordingly as the window is open at the top or bottom, for a distance equal to the 5 width of the opening; but they may not be

moved independently of one another, and therefore it is impossible for an intruder to open the window sufficiently to effect an entrance.

What I claim is—

1. In a sash-fastener, the combination with a guide-rod supported upon one window-sash, of a locking device coöperating with the guide-rod, said locking device comprising a head having a vertical recess for reception of the 45 guide-rod and an intersecting horizontal segmental recess, and a locking-piece embracing the head having a rotary reciprocating movement in the horizontal recess and adapted to be moved into and out of engagement with 50 the guide-rod, substantially as described.

2. In a sash-fastener, the combination with a guide-rod supported upon one window-sash, of a locking device coöperating with the guide-rod, said locking device comprising a head 55 having a vertical recess for reception of the guide-rod and an intersecting horizontal segmental or forked recess, and a segmental locking-piece embracing the head received in said horizontal recess and adapted to reciprocate 60 therein the arms of said locking-piece being left separated, substantially as described.

In testimony whereof I have signed my name to this specification in the presence of two subscribing witnesses.

ADEN J. ASHLEY.
